DESIGN FOR A COMBINED ASHTRAY, CIGARETTE SUPPORT, AND SNUBBER

Ray Rice Hutcheson, Frederick, Md., assignor to
The Everedy Company, Frederick, Md., a corporation of Maryland

Application February 7, 1939, Serial No. 82,846

Term of patent 3½ years

To all whom it may concern:

Be it known that I, Ray Rice Hutcheson, a citizen of the United States, residing at Frederick, in the county of Frederick and State of Maryland, have invented a new, original, and ornamental Design for Combined Ashtray, Cigarette Support and Snubber, of which the following is a specification, reference being had to the accompanying drawing, forming part thereof.

ashtray, cigarette support and snubber showing my new design;

Fig. 2 is a view partially in side elevation, taken substantially on line 2—2 of Fig. 1; and

Fig. 3 is a view partially end elevation, taken substantially on line 3—3 of Fig. 1.

I claim:

The ornamental design for a combined ashtray, cigarette support, and snubber, as shown.

RAY RICE HUTCHESON.
